Attorney

UNITED STATES PATENT OFFICE.

HENRY CHARLES GORE, OF DUNEDIN, NEW ZEALAND.

COMBINED NAIL PULLER AND CASE OPENER.

Application filed February 26, 1923. Serial No. 621,309.

To all whom it may concern:

Be it known that I, HENRY CHARLES GORE, a subject of His Majesty the King of Great Britain, residing at Princess Street and 5 Moray Place, in Dunedin, in the British Dominion of New Zealand, have invented certain new and useful Improvements in a Combined Nail Puller and Case Opener, of which the following is a specification.

10 The object of this invention is to provide a tool, preferably made of oval or round bar steel, and usually bent somewhat Z-shaped having specially formed ends for the purposes hereinafter set forth.

15 One end is especially adapted for pulling nails of the various shaped heads used for nailing up packing cases or the like, and the other end is adapted for such purposes as breaking wire or hoop-iron, and 20 is also adapted for use as a screw-driver if screws are encountered, and the tool also embodies means for ripping the metal of lined cases.

25 Referring to the accompanying drawing:—Figure 1 is a side elevation of the tool, and Fig. 2 is an inverted plan of the nail-pulling end. Fig. 3 is a plan view of the wire or band breaking portion of the tool, and Fig. 4 is a longitudinal section 30 through the slanting groove showing the chisel portion for ripping the metal of lined cases, at the inner end of the said groove.

35 The remaining figures are details to a larger scale. Fig. 5 is a cross-section on the line 5—5 (Fig. 1), showing the beveled sides of the tapered groove, and Figs. 6 and 7 are views similar to Fig. 5 showing modified forms of the device for pulling different nail heads. Fig. 8 is a cross-section through 40 line 8—8 (Figs. 1, 3 and 4), showing the cutting edges for breaking wire or the like.

45 A is the body of the tool, which is preferably round or oval in cross-section; and B is one end thereof, which is bored out and slotted so as to form a tapered groove adapted to be forced under nail-heads, assisted by a blow from a hammer on the roughened face of the buffer B³, which can be used as a hammer itself when needed, for replacing lids or the like.

50 C is the flattened upper end, a part there-

of terminating in the chisel edge C⁵ and C¹ a slot cut slantingly and with beveled sides for breaking, and the inner end of the said slot is sharpened for ripping metal linings, 55 at C². One end C³ projects slightly to serve as a screw-driver, and C⁴ is a wire-cutting nick.

The beveling shown at B, Fig. 5, is preferred for sunk-headed nails, but the other forms shown in Figs. 6 and 7 better adapt 60 themselves to other shaped heads. See B¹, B². The beveled slot shown in Fig. 8 is actuated by a sideways movement of the tool, while the cutting chisel point C² shown at the inner end, is used for ripping. Which ever portion of the tool is being used, the other end forms a convenient and guiding handle for using it. The tool may be made in any suitable size of any suitable material.

Having described my invention what I 70 claim and desire to patent is:—

1. A tool of the character described comprising a shank provided with an angularly bent part, said part having a flattened portion adjacent one end, said portion being 75 formed with a slot in a plane intersecting the flat surfaces of said portion and the terminal edge thereof, thereby bifurcating said portion, one of said bifurcations being provided with a chisel edge and the other terminat- 80 ing in a blunt edge in advance of said chisel edge, the walls of said slot being formed with shearing edges.

2. A tool of the character described comprising a shank having a flattened portion 85 adjacent one end, said portion being formed with a slot in a plane intersecting the flat surfaces of said portion and the terminal edge thereof, thereby bifurcating said portion, one of said bifurcations being provided with a chisel edge and the other terminat- 90 ing in a blunt edge in advance of said chisel edge, the side walls of said slot being formed with shearing edges and the end wall 95 of said slot being formed with a knife edge.

In testimony whereof, I affix my signature, in presence of two witnesses.

HENRY CHARLES GORE,

Witnesses:

HENTON MACAULAY DAVEY,
